CROSS-STITCH SEWING MACHINE

Anton Kierner, Union, N. J., assignor to Emil Prazak, Elizabeth, N. J.

Application May 30, 1942, Serial No. 445,166

5 Claims. (Cl. 112—98)

This invention relates to improvements in sewing machines; and the invention has reference, more particularly, to novel sewing machine mechanism for producing and applying cross-stitching to goods for decorative and other purposes.

The invention has for an object to provide in a sewing machine, a novel multiple needle stitch forming mechanism including means to oscillatingly rotate the reciprocable needle-bar about its longitudinal axis in timed relation to the stitch forming operations of the mechanism, whereby to apply, to the goods operated upon, a plurality of stitch formations in mutually crossed relation for decorative or other purposes.

The invention has for another object to provide novel needle-bar rotating means including actuating cam means driven from the power shaft of the sewing machine; wherein said cam means may be provided in various forms adapted, selectively, to produce either continuously running or uninterruptedly connected cross-stitches, or one or more cross stitch formations alternated with straight run stitch formations, whereby various cross-stitch designs may be produced as desired.

Other objects of this invention, not at this time more particularly enumerated, will be understood from the following detailed description of the same.

Illustrative embodiments of this invention are shown in the accompanying drawings, in which—

Fig. 1 is a side elevation of a sewing machine embodying the present invention, parts being broken away to show underlying mechanism; Fig. 2 is a top plan view of the needle-bar rotating means and its actuating cam means in one position; and Fig. 3 is a similar top plan view showing the needle-bar rotating means and its actuating cam means in another position.

Figs. 4, 5 and 6 are respectively plan views of goods having applied cross stitching and showing various positions of the needles carried by the needle bar as moved to effect the crossing of the stitch formations.

Fig. 7 is a detail view of a modified form of needle-bar rotating cam formed to so control the needle-bar rotative oscillation as to produce double cross stitch formations alternated with straight run stitch formations; and Fig. 8 is a plan view of goods having applied alternated cross stitch and straight run stitch formations produced by the mechanism including the cam of Fig. 7.

Fig. 9 is a detail view of another modified form of needle-bar rotating cam formed to so control the needle-bar rotative oscillation as to produce multiple cross stitch formations alternated with straight run stitch formations; and Fig. 10 is a plan view of goods having alternately applied multiple cross stitch and straight run stitch formations produced by the mechanism including the cam of Fig. 9.

Similar characters of reference are employed in the above described views, to indicate corresponding parts.

Referring to the drawings, the reference character 11 indicates a sewing machine head supported by a base 12. Mounted in the head 11 is the usual presser foot 13 and the vertically reciprocable needle-bar 14; the latter carrying at least a pair of laterally spaced needles 15—16. Journaled to extend through the head 11 is the power or drive shaft 17 of the machine, the same being driven by the pulley 18. On the forward end of said shaft 17 is fixed a crank wheel 19 connected with a knuckle 20 on the needle bar 14 by a link or connecting rod 21, whereby to impart operative vertical reciprocable movements to said needle bar and its needles. Supported on the head 11 are thread tensioning devices 22, through which are led threads *a* and *b* from suitably disposed sources of supply. From said tensioning devices the threads *a* and *b* are led through the eye 23 at the upper free end of the needle bar 14, to extend thence through the eyes of a guide bracket 24, suitably disposed and affixed to the forward face of the head 11, said threads passing thence to the respective needles 15 and 16, through the eyes of which they are respectively threaded. Beneath the base 12, and suitably disposed and driven in the usual manner, is a looper means 25 to cooperate with the sewing needles for stitch forming operations; the stitches produced being of the chain stitch type. A sewing machine of the above described type, including the usual feed-dog means (not shown), comprises a construction well known to the art, and provides the basic structure in connection with which the improvements, according to the principles and purposes of the present invention, are provided.

To operate the needle bar and its needles whereby to cause the produced stitch formations to cross each other in a cross stitch relation, the needle bar 14 is so arranged that it is capable of rotative movements about its longitudinal axis as well as of vertical reciprocation, and to this

end is rotatably related to the knuckle 20, but is retained against axial or longitudinal movement relative to the latter by collars 26-27 affixed to the needle bar so as to respectively abut the upper and lower ends of said knuckle 20. It will thus be obvious that the vertical reciprocation of the knuckle 20, produced by the crank wheel 19 and link or connecting rod 21, will be transmitted to the needle bar while nevertheless leaving the latter free for rotative movements about its longitudinal axis.

Means are provided for producing rotative movements of the needle bar, of desired degree (usually of an amplitude approximating 180 degrees), first in one direction and then in the other; each such movement being properly controlled and timed so as to occur while the needles 15-16 are raised out of the work *c* being operated upon, and above or free of the presser foot 13. The means for thus oscillatingly rotating the needle bar comprises an oscillator frame having a hub sleeve 30 pivotally supported on an upstanding fulcrum post 31 which is affixed to the top of the head 11, in laterally offset or spaced away relation to the upper free end portion of the needle bar 14, which projects exteriorly from and above said head. Affixed to said hub sleeve 30 are upper and lower horizontal frame plates 32 and 33, the same being vertically spaced apart for a distance somewhat in excess of the limits of the vertical reciprocable movement of the needle bar. Said frame plates are each provided with suitably shaped interior openings 34 through which the needle bar extends; these openings being so sized as to permit the frame plates to unimpededly oscillate or swing relative to the needle bar. Connected to and between the free end portions of said frame plates 32-33 is a vertical thrust bar 35. Affixed to said needle bar intermediate the frame plates 32-33 is a lever arm 36 having a bifurcate free end portion adapted to straddle and operatively engage with said thrust bar 35. One of said frame plates, preferably the lower frame plate 33, is provided with an outwardly projecting tail-piece or lever lug 37.

Affixed to the rear end of the head 11 is a bracket member 38 which carries a laterally offset perpendicular bearing portion 39. Journalized in said bearing portion 39 is a cam shaft 40, upon which is fixed a worm gear 41 adapted to mesh with and be driven by a worm 42 on the power or drive shaft 17 of the machine. Affixed to the upper end of said cam shaft 40 is a cam wheel 43 having a cam race to engage and actuate means for transmitting operating motion to the heretofore described oscillator frame, in such manner, however, as to properly time and relate such motion to the operative reciprocations of the needle bar. The transmission means thus actuated by the cam wheel comprises a link bar 44 which is pivotally connected with the free end of a fulcruming bar 45, the opposite end of the latter being pivotally supported by and connected with a fixed supporting bracket 46 suitably located and attached to the head 11. The rearward end of said link bar 44 is provided with a roller stud 47 to operatively engage in the cam race of the cam wheel 43. The forward end of said link bar 44 is pivotally coupled with the tail-piece or lever lug 37 of the oscillator frame.

The race of the cam wheel 43 may be variously designed and formed according to the arrangement of cross stitch formations desired to be pro-

duced. In a simple form thereof, as shown more particularly in Figs. 2 and 3 (the cam wheel 43 being rotated in a clockwise direction), the same comprises a cam section 50 for moving the link bar 44 forwardly, to swing the oscillator frame in one direction whereby to rotate the needle bar clockwise, a following concentric dwell section 51 to hold the needle bar in the resultant position, a second cam section 52 for moving the link bar 44 rearwardly, to swing the oscillator frame in the opposite direction whereby to rotate the needle bar anti-clockwise, and a following or second dwell section 53 to hold the needle bar in position resulting from such movement, said dwell section 53 leading back to the first cam section 50, and thus completing the operative circuit of the cam race.

In the operation of the machine, when the laterally spaced needles 15 and 16 (which, for stitch completing operation, are normally disposed on a line transverse to the path of movement of the work *c* through the machine) have been positioned with the needle 15 at the right and the needle 16 at the left (see Fig. 4) by a previously effected swing of the oscillator frame in anti-clockwise direction, such swing being produced by the traverse of the cam section 50 of the cam race along the roller stud 47 of the link bar 44, said roller stud is engaged and traversed by the dwell section 51 of the cam race, whereby the link bar 44 and oscillator frame are held stationary, so as to retain said needles 15 and 16 in the aforesaid relative positions (see Fig. 2). While the needles are held in said positions, the work *c* having in the meantime been fed forward by the machine work feed means, the needle bar reciprocating means causes the needles to descend and enter through the work *c*, so that the looper hooks *x* and *y* (which are respectively arranged with their hook sides inward for proper engagement and manipulation of the needle borne threads *a* and *b*) respectively engage said threads *a* and *b* to form stitch locking chain loops in the well known manner, whereupon the downward movement of the needle bar 14 is reversed so that the needles 15 and 16 are raised out of the work *c* and free of the presser foot 13. By the time the needles clear the presser foot 13, the dwell section 51 of the cam race completes its traverse of the link bar roller stud 47, so that the latter is thereupon engaged and traversed by the second cam section 52 of the cam race, during which time the needle bar completes its upward movement and again starts downward on its operative stroke, and also during which time the work *c* is fed forward to initiate a cross stitch formation. The engagement of the stud roller 47 by said second cam section 52 operates to retract the link bar 44, and thereby causes the oscillator frame to swing in clockwise direction (see Fig. 3). Such clockwise movement of the oscillator frame is transmitted by its thrust bar 35 through the lever arm 36 to the needle bar 14, thereby rotating the latter in clockwise direction, and thus revolving the needles 15 and 16 approximately 180 degrees, so as to reverse the position of said needles to dispose the needle 16 at the right and the needle 15 at the left (see Figs. 5 and 6). Such revolution of the needles, while the work *c* is advanced by the feed means of the machine, causes the threads *a* and *b* to cross each other. After the needles are thus positioned, the second cam section 52 having completed its traverse of the link bar roller stud 47, the second dwell section 53 of the cam race engages and traverses the link bar

stud roller, so that the link bar and oscillator frame are held stationary, and the needle bar is held against rotation, while the needles 15 and 16 again enter and leave the work *c*, whereby to complete one cross-stitch formation and initiate a succeeding cross-stitch formation. The above described operations are continuously repeated during the operation of the machine, so that continuously following and connected cross-stitch formations are successively produced. In the illustrative form of cam wheel above described and as shown in Figs. 2 and 3, two such cross-stitch formations are produced during each revolution of the cam wheel 43.

As previously hereinabove intimated the race of the cam wheel 43 may be shaped to produce other than continuously following and connected cross-stitch formations. Illustrative examples of modified cam race forms are shown in Figs. 7 and 9, and it will be understood that many other modified forms may be utilized.

In the cam wheel 43 shown in Fig. 7, the cam race is designed so that, in operation, it will control and time the movements of the oscillator frame relative to needle bar reciprocation whereby to produce, two successive cross-stitch formations *ab* in alternation with straight stitch formations *s* (see Fig. 8). To this end, as also indicated by the legends applied in Fig. 7, the cam race is divided into groups of succeeding sections, comprising a cam section TF for turning the needle bar and its needles in one direction, a dwell section EL to hold the needle bar and its needles against turning while entering and leaving the goods, (making one cross-stitch formation), a cam section T'F for turning the needle bar and its needles in the opposite direction, a dwell section EL to again hold the needle bar and its needles against turning while entering and leaving the goods (making the second cross-stitch formation), a continuing dwell section S to continue to hold the needle bar and its needles against turning while the goods are fed and straight stitches are formed, and another dwell section EL to hold the needle bar and its needles against turning while entering and leaving the goods, whereby to complete the straight stitches and initiate a succeeding cross-stitch formation.

It will be obvious that by providing the cam race with dwell sections EL, S, EL between the cam sections TF and T'F, instead of an EL section only, the stitches produced will comprise single cross-stitch formations alternated with straight stitch formations.

In Fig. 9 is shown another modified form of cam wheel 43 wherein the cam race is designed to control and time the movements of the oscillator frame so as to produce a plurality of successive cross-stitch formations *ab*, e. g., four, in alternation with straight stitch formations *s* (see Fig. 10). To this end the cam race is divided into groups of succeeding sections TF, EL, T'F, EL, TF, EL, T'F, EL, S, and EL respectively functioning in the same manner as the correspondingly identified sections in Fig. 7, with the result, in operation, of continuously producing four successive cross-stitch formations followed by a straight stitch formation as shown in Fig. 10.

From the above description it will be understood that the machine will function in a simple and efficient manner to form and apply to the surface of goods worked upon desirably arranged cross-stitch formations for decorative or other purposes. The stitch forming mechanism has been illustratively shown and described as of

the type producing a chain stitch, but it will be obvious that the sewing mechanism may be modified to produce any other well known type of stitch locking formation.

Many changes other than those already mentioned may be made in the above described construction, and widely different embodiments of this invention could be made without departing from the scope thereof as defined by the appended claims. It is therefore intended that all matter contained in the above description and shown in the accompanying drawings shall be interpreted as illustrative and not in a limiting sense.

I claim:

- 15 1. In a sewing machine for producing cross-stitch formations, a stitch forming mechanism including a reciprocable needle bar carrying laterally spaced needles respectively supplied with individual threads, said needle bar being capable of rotative movement in addition to its reciprocable motion, a pivoted oscillator means carrying a thrust bar disposed parallel to the needle bar, said needle bar having a laterally projecting lever arm engaged by said oscillator means thrust bar, whereby the latter imparts rotative movements to said needle bar so as to alternately transpose its needles prior to stitch completing operations of said needles, and means for actuating said oscillator means in timed relation to reciprocable movements of said needle bar, said latter means including a driven control cam.
- 20 2. In a sewing machine for producing cross-stitch formations, a stitch forming mechanism including a reciprocable needle bar carrying laterally spaced needles respectively supplied with individual threads, said needle bar being capable of rotative movement in addition to its reciprocable motion, a pivoted oscillator means carrying a thrust bar disposed parallel to the needle bar, said needle bar having a laterally projecting lever arm formed to slidingly embrace said thrust bar, a driven cam wheel having a cam race, and a link bar coupled to said oscillator means and having a stud engaged by said cam race, said cam wheel being adapted to transmit, through said link bar, back and forth swinging movements to said oscillator means for transmission by its thrust bar to said needle bar lever arm, whereby to correspondingly rotate said needle bar to transpose its needles with thread crossing effect prior to given stitch completing operations thereof.
- 25 3. In a sewing machine for producing cross-stitch formations as defined in claim 2, wherein the cam wheel race is so shaped as to swing the oscillator means and thereby rotatively oscillate the needle bar in such manner and timed relation to selected reciprocable movements thereof as to produce one or more cross-stitch formations alternated with straight stitch formations.
- 30 4. In a sewing machine for producing cross-stitch formations, a stitch forming mechanism including a reciprocable needle bar carrying laterally spaced needles respectively supplied with individual threads, said needle bar being capable of rotative movement in addition to its reciprocable motion, a pivoted oscillator means carrying a thrust bar disposed parallel to the needle bar, said needle bar having a laterally projecting lever arm formed to slidingly embrace said thrust bar, a driven cam wheel having a cam race, a link bar, a pivoted fulcruming bar to which said link bar is pivotally connected, the forward end of said link bar being pivotally coupled to said oscillator means, the rearward end of said link bar having a stud engaged by said cam race, said cam wheel

being adapted to transmit, through said link bar, back and forth swinging movements to said oscillator means for transmission by its thrust bar to said needle bar lever arm, whereby to correspondingly rotate said needle bar to transpose its needles with thread crossing effect prior to given stitch completing operations thereof.

5. In a sewing machine for producing cross-

stitch formations as defined in claim 4, wherein the cam wheel race is so shaped as to swing the oscillator means and thereby rotatively oscillate the needle bar in such manner and timed relation to selected reciprocable movements thereof as to produce one or more cross-stitch formations alternated with straight stitch formations.

ANTON KIERNER.
